E. D. AVERILL.
RULING PAPER BY ELECTROMAGNETISM.

No. 60,663.

Patented Jan. 1, 1867.

Inventor;

Elliott D. Averill
by G. P. Shoffner
attorney &

United States Patent Office.

ELLICOTT D. AVERELL, OF NEW YORK, N. Y.

Letters Patent No. 60,663, dated January 1, 1867.

IMPROVEMENT IN RULING PAPER BY ELECTRO-MAGNETISM.

The Schedule referred to in these Letters Patent and making part of the same.

TO ALL WHOM IT MAY CONCERN:

Be it known that I, ELLICOTT D. AVERELL, of the city of New York, in the State of New York, have invented a new and improved mode of "Ruling Paper by the aid of Electro-Magnetism;" and I do hereby declare that the following is a full and exact description thereof, reference being had to the accompanying drawings, and to the letters of reference marked thereon.

The nature of my invention consists in the fixing of an electro-magnet at one end of a pen-board of the ordinary ruling machine, having attached thereto an armature, in combination with the circuit-breaker finger described in my Letters Patent dated June 12, 1866, No. 55,594. The wires surrounding the magnets are connected with fingers attached to the mechanism in such manner as will be moved by the paper passing over the endless cloth or other band, and when moved, to open or close an electric circuit composing the surroundings of the electro-magnet bobbins or spools. When the paper passes with the endless band, it moves the finger, which, acting as a key to the electric circuit, opens or closes the circuit. When closed, the Voltaic current passes around the electro-magnets, and at that moment magnetizes the cores of the said magnets, which immediately attracts the armature attached to the pen-board, and then the pens mark the paper as desired. The mechanism required to open and close the electric circuit is embraced in my Patent No. 55,594 for an improvement on ruling machines.

To enable others skilled in the art to make and use my invention, I will proceed to describe its construction and operation; the said invention being an improvement on my Patent No. 55,594.

I construct my electro-magnet similar to those used for telegraphic purposes; but the armature is attached to a board carrying one or more pens, such as are used in the ordinary ruling machines in book binderies. The electro-magnet, when acted upon by a current of electricity, attracts the armature carrying the pens down upon the paper, and, when uncharged, a spring carries the pen-board up from the paper. The charging and uncharging the wire surrounding the electro-magnet is done by a circuit-breaker operated upon by contact with the sheet of paper to be ruled.

Figure 1 represents a view of the machine complete.

A is the electro-magnet, B the armature carrying the pen-board, C the carrying band; E E conveys the paper to be ruled, which strikes against the circuit-breaker finger at F; which closes the circuit at G, and thus charging the wire around the electro-magnet A, causing the armature, B, to descend, bringing the pen-board down so as to allow the pens to strike the paper.

Figure 2 is an enlarged view of the circuit-breaker and contact finger.

Having fully described the nature of my invention, and the mode of operating it, what I desire to secure by Letters Patent, is—

I claim the application of an electro-magnet for the purposes of ruling paper, in combination with the circuit-breaker finger F, in the manner and substantially as described in the foregoing.

ELЛИCOTT D. AVERELL.
